UNITED STATES PATENT OFFICE.

PAUL P. GREDELL, OF QUINCY, ILLINOIS.

GRATE.

1,112,999.

Specification of Letters Patent.

Patented Oct. 6, 1914.

Application filed May 8, 1914. Serial No. 837,241.

To all whom it may concern:

Be it known that I, PAUL P. GREDELL, a citizen of the United States, residing at Quincy, in the county of Adams and State 5 of Illinois, have invented a new and useful Grate, of which the following is a specification.

The device forming the subject matter 10 of this application is an auxiliary or secondary grate, adapted to be placed above the main grate of a stove, furnace or other burner.

The invention aims, primarily, to provide 15 a novel form of secondary grate of the type above mentioned, which secondary grate may without difficulty be set in a furnace or stove and, with equal facility be taken down, the construction being such that any one of the bars which go to make up the 20 secondary grate may be renewed readily.

It is within the scope of the invention to improve generally and to enhance the utility of devices of that type to which the present invention appertains.

25 With the above and other objects in view which will appear as the description proceeds, the invention resides in the combination and arrangement of parts and in the details of construction hereinafter described 30 and claimed it being understood that changes in the precise embodiment of the invention herein disclosed can be made within the scope of what is claimed without departing from the spirit of the invention.

35 In the accompanying drawing:—Figure 1 shows in vertical transverse section, a device constructed in accordance with the present invention; Fig. 2 is a bottom plan of one of the grate bars; Fig. 3 is a side elevation of one of the grate bars; Fig. 4 is a top plan of one of the grate bars; Fig. 5 is a fragmental longitudinal section of the ring or support on which the grate bars are mounted; Fig. 6 is a side elevation of 45 one of the legs which, being assembled with the support, constitute means whereby the secondary grate is upheld.

In the accompanying drawings, the numeral 1 indicates the fire pot of a furnace, 50 the word "furnace" being used to designate any structure with which the device forming the subject matter of this application is adapted to be assembled. The fire pot 1, ordinarily, is provided adjacent its lower 55 end with an inwardly projecting ledge 2.

The main grate, which may be of any desired form, is denoted by the numeral 3.

The device forming the subject matter of the present application is a secondary grate, adapted to be disposed in the fire pot 60 1 above the main grate 3. In the form of the invention under discussion, there is provided an annular support 4, preferably in the form of a ring, the support 4 being made of a bar of metal, the ends of which may 65 be united, as shown in Fig. 5, by means of a securing strip 9 held in place by rivets 10, although any other construction may be employed at this point if deemed expedient. The support 4 is upheld on a plurality of 70 legs 5, four legs ordinarily being employed. Each leg 5 is equipped adjacent its upper end with an enlarged boss 6 having an opening 7 receiving the support 4. Preferably, the support 4 is of rectangular cross section 75 and the openings 7 are shaped accordingly, so that the legs 5 will not rotate on the support 4.

In carrying out the invention there is provided a plurality of bars 11, each bar 11 80 comprising a body portion 12 at the upper end of which is formed a laterally inclined arm 14, the lower end of the body 12 terminating in a tongue 15 which is inclined with respect to the body 12 as Fig. 3 will 85 clearly show. On the rear edge of the body portion 12 of each bar 11 adjacent the point of juncture between the body 12 and the tongue 15 there is formed a boss 16 in the lower edge of which is fashioned a downwardly opening notch 17 defining a finger 18. Each bar 11 is provided adjacent its upper end and at one side with a spacing lug 19 and above the spacing lug 19 but upon the opposite side of the bar therefrom 95 is formed a spacing lug 20. The lower edge of the spacing lug 20 is in approximate alinement with the upper edge of the spacing lug 19. Adjacent its lower edge, each bar 11 is provided with a laterally extended 100 spacing lug 21, extended in the same direction as the lug 20.

In practical operation, the notches 17 in the bars 11 receive the support 4, the bars slanting outwardly to form an inverted, 105 frusto-conical grate, and the upper arms 14 of the bars being received by the fire pot 1, as Fig. 1 will clearly show.

Noting particularly Fig. 1, it will be noted that the fingers 19 and 20 on the re- 110

spective bars coöperate to form a double width ring adjacent the top of the grate, the lugs 21 coöperating to form a single width ring adjacent the bottom of the grate.

5 One of the main advantages incident to the present invention is that the structure may be assembled readily in the fire pot 1, and with equal facility be taken down, it being possible to remove without difficulty, 10 any one of the bars 11 which may have become burned out or damaged. Owing to the construction of the device as above outlined, it will be observed that the secondary grate device may be made to fit readily in 15 a fire box, although the same may have become slightly warped.

The secondary grate allows a free circulation of air and it does not permit the accumulation of clinkers. The fuel does not 20 become clogged, the fuel consumption is lessened, smoke and gases will be readily consumed, and the fire will burn more evenly, when the secondary grate above described is used.

25 Having thus described the invention, what is claimed is:

1. In a device of the class described, an annular support; and outwardly inclined upwardly extended bars assembled with the 30 support to form an inverted frusto-conical grate, each bar being provided with oppositely extended spacing lugs upon its edges, the upper edge of one lug on each bar being alined with the lower edge of the other lug 35 on the same bar, whereby the respective lugs on adjoining bars will coöperate to form a double width ring adjacent the top of the grate.

2. In a device of the class described, an 40 annular support; and outwardly inclined upwardly extended bars assembled with the support to form an inverted frusto-conical

grate, each bar being provided with oppositely extended spacing lugs upon its edges, the upper edge of one lug on each bar being alined with the lower edge of the other lug on the same bar, whereby the respective lugs on adjoining bars will coöperate to form a double width ring adjacent the top of the grate, each bar being provided near 45 its lower end with a single spacing lug, the single lugs coöperating to form a single width ring about the grate adjacent the lower end of the grate.

3. In a device of the class described, a fire 55 pot; an annular support; legs between which the support passes, the legs engaging the fire pot; a plurality of outwardly slanting upwardly extended bars, each bar being provided adjacent its lower end in its outer edge with a downwardly opening notch which receives the support, the upper ends of the bars resting against the fire pot, and the bars coöperating to form an inverted, frusto-conical grate, each bar being provided with oppositely extended spaced lugs upon its edges, the upper edge of one lug 60 on each bar being alined on the lower edge of the other lug on the same bar, whereby the respective lugs on adjoining bars will 65 coöperate to form a double width ring adjacent the top of the grate, each bar being provided near its lower end with a single spacing lug, the single lugs coöperating to form a single width ring adjacent the lower 70 end of the grate.

In testimony that I claim the foregoing as my own, I have hereto affixed my signature in the presence of two witnesses.

PAUL P. GREDELL.
